UNITED STATES PATENT OFFICE.

WILLIAM E. HOYT, OF NEW YORK, N. Y.

SAD-IRON.

No. 838,997.

Specification of Letters Patent.

Patented Dec. 18, 1906.

Application filed December 19, 1904. Serial No. 237,457.

To all whom it may concern:

Be it known that I, WILLIAM E. HOYT, a citizen of the United States, residing at New York, in the county of New York and State 5 of New York, have invented certain new and useful Improvements in Sad-Irons, of which the following is a specification.

This invention relates to improvements in sad - irons having a combustion - chamber 10 formed within its interior, wherein a suitable material, such as charcoal, is burned for the purpose of heating the iron to a temperature which will enable it to be used for all ironing purposes continuously throughout a whole 15 day's work, if necessary, without the trouble and delay of heating the iron on a stove.

It is well known that the weekly ironing is one of the most arduous tasks which confronts the housekeeper, particularly during 20 the hot summer weather, when the person performing those operations with the well-known solid irons is required to labor in the vicinity of a hot stove on which to heat the irons; but with an iron of the so-called "self-heating" type, which includes my invention, the ironing may be done in some cool retreat, even under the shade of a tree where the person performing the labor can be fanned by every breeze that blows instead of being 25 pressed to the verge of prostration between the four walls of a heated room. Under such conditions as are made possible by inventions like this the small charcoal fire required within the iron to heat it will be in- 30 appreciable to the operator or ironer.

An important object of my invention is to provide means for retaining the position of the movable door when the latter is elevated to allow a free access of air to the grate-bar, 40 which forms a flue under the bed of charcoal.

Another object of my invention is to provide a sad-iron that will be thoroughly efficient and practicable, that can be produced at a moderate cost, and that will be provided 45 with a fluting device that will not make the iron cumbersome or inconvenient.

I accomplish the objects of the invention by the mechanism illustrated in the accompanying drawings, in which—

50 Figure 1 is an end view looking at the rear of my improved sad-iron with the door closed. Fig. 2 is a longitudinal vertical section on the line 2 2 of Fig. 1, showing the door at the end in elevated or open position. Fig. 3 is a detail in vertical section of the rear end of the iron on the same plane as the section in Fig.

2, showing the door in its lower or closed position in full lines and in its raised position in dotted lines. Fig. 4 is a detail in perspective of the grate-bar of the iron. Fig. 5 is a detail in perspective showing the body of the iron with the end door and the top of the iron removed, and Fig. 6 is a perspective of the iron turned on its side with a fluting device applied to the latter and in operative position. Fig. 7 is a view in transverse vertical section of my iron.

Like characters of reference indicate like parts throughout the several views of the drawings.

70 7 is the body of the iron, which is of usual shape and size and is made hollow to form a chamber which is open at the rear end of the iron. This opening has the flanges 8 at each side thereof to form guides to retain and direct the sliding door or gate 9. Both sides of this body have air-holes 10, and located within the body against the side walls thereof are the sliding damper-plates 11, one on each side of the iron, which are connected by the bridge-plate 40, whereby said damper-plates 11 will have simultaneous movement. The 75 said plates 11 have suitable openings which are brought into register with the openings in the sides of the iron more or less completely 80 by the longitudinal movement of said plates.

85 12 is the top of the iron, having a chimney 13 for the escape of the waste products of combustion and for the complete ventilation or draft of the iron. This chimney has the 90 damper 14 for the purpose of regulating the draft. At the opposite end of said top from the chimney is the standard 15, which forms one of the connections for a handle 16, the opposite end of said handle being supported 95 by attachment to the wall of chimney 13. A

heat-deflector 17 is interposed between the top of the iron and the handle. The top 12 also has the under-side flanges or lugs 18 to fit inside of the walls of the body near the top of the latter to which they are fastened by screws 19. 20 is a sheet-metal lining fastened by screws 19, above mentioned. This lining is held by the ribs 21 away from the outer side walls of the iron, so as to produce 105 air-passages at the sides of the combustion-chamber. This lining terminates at a suitable distance above the bottom of the combustion-chamber to allow for the discharge of air under it into the iron from the passageways above referred to.

110 22 is a lever which rests upon the top 12 of

the iron and is pivoted at one end thereto by means of the screw 23. The top of the iron has a longitudinal slot 24, through which a rivet 25 passes to connect the lever with the 5 cross-bar 40, connecting the side dampers 11. The free end of the lever is provided with a knob for the convenient shifting of the lever by pressure with the thumb of the operator to thereby change the position of the plates 11 10 and regulate the supply of air through the sides of the iron.

Located within the iron upon the bottom thereof is a false bottom 26 with air-passages between it and the real bottom of the iron. 15 Preferably there will be three passage-ways occupying practically the whole width of the bottom adjacent to the door, but the two outside ways will terminate at about one-fourth of the length of the combustion-chamber in from the door, while the middle 20 passage will extend nearly the entire length of the interior of the iron. These passages open at their ends into the combustion-chamber and they have additional top openings 25 27 thereto. The reason that the outer passages do not extend as far into the combustion-chamber as the middle one is that they keep the charcoal from contact with the bottom of the iron to such an extent as to interfere with the heating of the latter.

The to-and-fro movement of the iron as used will cause an air circulation through it if proper openings are provided; but as a rapid movement would force more air through the same openings than a slow movement it is necessary to provide means for regulating the size of the air-inlets.

In my invention I make the door 9 hollow and close the chamber thus formed with an 40 inside plate 28, having a number of evenly-distributed openings 29 to distribute the air equally to the whole mass of fuel. The outer wall of the chamber has the air-openings 30 closed by the sliding damper 31, having 45 the usual openings, whereby the size of the air-inlets to said chamber may be regulated. At certain times, as when the charcoal fire in the iron burns too low or in starting the fire at the beginning of the operation 50 of ironing, it is desirable to raise the door into the position shown in Fig. 2 with the lower end of the door resting upon the hollow false bottom or grate 26. The latter has the rib or flange 47 next to the end, and the door 55 has a bottom flange to engage the flange 47, thereby forming a lock, which will prevent the easy displacement of the door when thus placed in elevated position. As the door in order to be tilted into the position shown in 60 Fig. 2 must fit loosely within the flanged end of the body 7 it will be liable to displacement by the jar occasioned by the movement of the iron from the position shown in Fig. 2, and in order to hold it securely against such 65 displacement and to cause it to assume this

oblique position when raised I provide the spring 32, which has its upper end fastened, by means of a screw 33, to the standard 15 and has the angular portion 34 bent out, so as to stand in the path of the door when the latter is raised and by pressure against the raised upper end of the door to press said upper end in an outward direction against the tops of flanges 8 as a fulcrum, thereby causing the lower end of the door to move inwardly to a position where its bottom flange will lie inside of flange 47 on the grate-bar. The standard 15 has a socket 36 to receive the end of spring 32 when the latter is pressed in by the action of the door, as above 80 described, and in order to facilitate the compression of the spring by contact with it of the door when the latter is raised I form its lower end into the oblique member 37.

Having thus fully described my invention, 85 what I claim as new, and wish to secure by Letters Patent, is—

1. In a hollow sad-iron in which charcoal is burned to heat it, a false bottom for said iron having under side air-passages, and a 90 transverse upwardly-projected rib or flange at its outer end, a vertically-sliding door capable of swinging inwardly at its lower end to rest upon said false bottom, and a spring to press against the door and swing its inner 95 end inwardly when the door is raised.

2. A hollow sad-iron having hollow walls with damper-regulated openings in said hollow walls, a false bottom for said iron having air-passages with top and end openings into 100 the combustion-chamber of the iron, and said false bottom having an upwardly-projected rib at its outer end, a vertically-sliding door capable of swinging in at its lower end to 105 rest upon the false bottom when the door is sufficiently elevated, and a spring secured to the iron and adapted to press against the door to swing the lower end of the latter inwardly when the door is raised.

3. A hollow sad-iron having a combustion-chamber in which charcoal is burned to heat it, said chamber having air-passages in its walls and dampers to regulate the air-passages therethrough, said iron having a vertical standard at its rear end, a false bottom 110 for said iron having air-passages, with openings into the combustion-chamber, vertical flanges at the rear open end of the iron, a sliding door secured by said flanges and adapted when raised above the false bottom 115 to swing inwardly at its lower end and engage the end of said false bottom, and a spring fastened to said standard and having its free end in the path of the door when the latter is raised, said spring being adapted to 120 press the upper end of the door out thereby causing its inner end to swing inwardly into engagement with said false bottom.

4. In a sad-iron, a hollow body in which charcoal is burned to heat it, said iron having 130

a chimney at its front end and a standard at its rear end, a handle supported by the chimney and standard, said standard having a socket, a spring fastened at its upper end to the standard and having an angular outwardly-projected bend at its lower end terminating with an oblique portion which enters the socket when the spring is pressed toward the standard, flanges at the rear open end of the sad-iron, a door held by said flanges and adjustable vertically between the flanges and the other portions of the iron and

adapted to be pressed outwardly at its upper end by said spring whereby its lower end will be made to swing inwardly into engagement with said false bottom when the door is raised. 15

In witness whereof I have hereunto set my hand and seal, at Indianapolis, Indiana, this 2d day of December, A. D. 1904.
